(57) CLAIM

The ornamental design for a handbag, as shown and described.

DESCRIPTION

FIG. 1 is a front perspective view of a handbag showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of the handbag, shown with a shoulder strap.

The dot-dashed broken lines showing the shoulder strap, clasp, and D-shaped rings are for the purposes of illustrating environment and form no part of claimed design.

The dashed lines associated with the edges of panels of the handbag, handle, handle's mounts, handle's interwoven applied ribbon, denote stitching and constitute portions of the claimed design.
